ADJUSTABLE HEADBAND FOR INDUSTRIAL
HEADGEAR

Werner I. Staaf, Rennerdale, Pa.

Application October 21, 1944, Serial No. 559,802

11 Claims. (Cl. 2-8)

1

This invention pertains to headgear used industrially for safety purposes, such for example as safety vizors, welding vizors, guards, and the like, and is for an improvement in an adjustable head band for such devices.

Headgear of the class to which the present invention pertains, usually has a head band that encircles the head, and a strap that goes over the head and joins to the head band at diametrically opposite points. The head band serves to support a vizor or other protecting guard. These head bands are adjustable over a relatively wide range. Adjusting mechanism as heretofore constructed, has been of a character which is difficult, if not impossible for the operator himself to adjust while the head band is in position on the head, and it has also been of a character in which the hair easily becomes entangled.

According to the present invention, there is provided a simple adjustment for head bands of this character whereby the operator may easily adjust the head band, even while the same is in place, and in which the hair of the wearer is not likely to become entangled.

According to the present invention as generally constructed, there is provided an adjusting mechanism in which a rotatable thumb nut accessible at the rear of the head band is utilized to turn two oppositely threaded spiral elements simultaneously. The head band itself is provided with projections that engage in these spiral elements, the spiral elements preferably being flexible spiral springs so that the turning of the thumb nut causes motion to be transmitted to the opposite ends of the head band. The mechanism is entirely enclosed, except for the periphery of the thumb nut.

The invention may be more fully understood by reference to the accompanying drawings, in which:

Fig. 1 is a top plan view of an industrial eye shield embodying my invention;

Fig. 2 is a side elevation thereof;

Fig. 3 is a detail view on a larger scale, showing the adjusting mechanism, the view being a horizontal section through the head band in substantially the plane of line III—III of Fig. 4; the springs and thumb nut being shown in elevation;

Fig. 4 is a transverse vertical section in the plane of line IV—IV of Fig. 3;

Fig. 5 is a detail view showing one end of the head band; and

Fig. 6 is a detail view showing one of the spring engaging elements used in the head band.

2

Referring to the drawings, the headgear which, per se, is of more or less conventional form, comprises a head band 5 having two end portions 5a and 5b. Suspended from the front of the head band is a transparent vizor 6. Attached to diametrically opposite sides of the head band are the opposite ends of a strap 7 which goes over the top of the head of the wearer, the strap 7 being retained in place by bolts 8 carrying thumb nuts 9. There is also an adjustable vizor 10 pivotally supported on the bolts 8, and which is frictionally held in position by the thumb nuts 9.

According to the present invention as preferably embodied, each of the two ends 5a and 5b of the head band is provided with a clip of the form shown in Figs. 5 and 6. This clip has a base portion 11 and two ears 12 which are passed through the head band and pressed down against the head band as shown in Fig. 5, the base also carrying a single upstanding lug 13 that passes through the head band and projects perpendicularly to the surface of the head band. The head band itself may be of flexible fiber, leather, or thin metal.

The two ends 5a and 5b of the head band lap over a metal supporting plate 14, which is curved to an appropriate degree and which, as shown in Fig. 4, is wider than the head band, this curved supporting plate having edge portions 15 that are turned over to provide channels or grooves along each edge thereof. Slidably received in these channels or grooves 15 is a curved cover plate 16 having lip portions 16a that are received in the edges 15, and having sloped ends 17, the central portion 16b of the cover 16 providing a longitudinally extending internal channel 16c. Midway between its ends the cover 16 has a transverse slot 18 therein. A knurled thumb nut 19 is positioned under the cover and its periphery projects through the transverse slot 18. The thumb nut 19 has oppositely extending projections 20. Soldered to one projection 20 is a coil 21a preferably of spring metal, and to the other projection 20 a similar coil 21b, these coils being received in the central channel 16c of the cover and being spiraled in opposite directions. The projecting lug 13 on the end 5a of the head band engages between the convolutions of the spring 21a and the projection 13 on the end 5b of the head band engages in the convolutions of the spring 21b.

The thumb nut or disc 19 may be rotated in either direction, and when it is so rotated, it turns the coils or springs 21a and 21b. This

in turn causes the motion to be transmitted to the lugs or projections 13, causing the ends of the head band to slide on the plate 14 toward or away from each other.

The springs 21a and 21b being flexible of course adapt themselves to the longitudinal curvature of the housing 16 and flex as they are being rotated, so that the turning action is smooth and uniform, whereas, of course, rigid threaded elements could not be so curved. The thumb nut 19 is retained in place by the cover 16 and the boundaries of the slot 18, and also when pressure is put on its periphery to turn the springs, its inner periphery may contact the plate 14.

In assembling the adjusting mechanism, the thumb nut with its attached springs is set in position in the cover 16 with the coils in the channel 16c. The two ends of the head band are then brought into place and the projections 13 properly entered between the convolutions of the respective springs. Then the base plate 14 is slipped into place inside of the ends of the head band and with its channel portions 15 embracing the edges of the cover 16.

The adjusting mechanism is extremely simple, is cheap to manufacture, and is easily operated. Because it can be quickly and easily adjusted by the operator, the operator is less likely to be careless in the use of the headgear than where the use of the device involves difficult adjustments. The housing or cover 16 in conjunction with the plate 14 completely encloses the adjusting mechanism, there being only a narrow slot under the sloping ends 17 of the cover 16 through which the ends of the head band slide. Consequently the hair of the operator cannot become entangled in the device. While two coils are provided to simultaneously adjust both ends of the band, it is apparent that a single coil moving only one end of the strap might be simply provided. The springs 21a and 21b being resilient, have a slight yield or give lengthwise that is desirable in allowing a slight stretch of the head band and also make the mechanism more free turning because binding does not occur.

While I have illustrated and described one specific embodiment of my invention, it will be understood that various changes and modifications may be made within the contemplation of my invention and under the scope of the following claims.

I claim:

1. A headgear having a head band with opposed end portions, a housing in which the end portions are received, a pair of oppositely curved coils in the housing, each coil extending along one of the said end portions, means on each end portion engaging the convolutions of the coil which extends therealong, and means for rotating the coils.

2. A headgear having a head band with opposed end portions, a housing in which the end portions are received, a pair of oppositely curved coils in the housing, each coil extending along one of the said end portions, means on each end portion engaging the convolutions of the coil which extends therealong, and means for simultaneously rotating both of the coils in the same direction.

3. A headgear having a head band with opposed end portions, a housing in which the end portions are received, a pair of oppositely curved coils in the housing, each coil extending along one of the said end portions, means on each end portion engaging the convolutions of the coil

which extends therealong, and means for simultaneously rotating both of the coils in the same direction, said last named means comprising a thumb nut retained within the housing and having its periphery projecting beyond the housing.

4. In a headgear having an adjustable head band with opposed end sections, adjusting mechanism for moving one end section relative to the other comprising a coil and carried in a support 10 with respect to which said one end is longitudinally movable, means for turning the coil, and means on the said one end section engaged in the convolutions of the coil.

5. In a headgear having a head band which 15 is adjustable, the head band having opposed end portions movable relatively toward and away from each other, an adjusting mechanism comprising a coil element extending lengthwise along one of the end sections and carried in a support with 20 respect to which said one end is longitudinally movable, means on the end section engaging the convolutions of the coil element, and means for rotating the coil element.

6. A headgear having a head band with opposed 25 end portions, a housing in which the end portions are received, a pair of coils in the housing, one coil extending along each of the said end portions, means on each end portion engaged in the convolutions of the coil which extends 30 therealong, and means for turning the said coils.

7. A headgear having a head band with opposed end sections, a curved plate over which the end sections extend, a curved housing having a longitudinal channel secured to said plate, a pair of 35 oppositely wound coil elements in said channel, one coil element extending lengthwise along each end section, a projection on each end section engaging the coil element that extends therealong, and means accessible at the exterior of the hous- 40 ing for simultaneously rotating both coil elements.

8. A headgear having a head band with opposed end sections, a pair of oppositely wound spiral elements connected with a common operating means, one element extending along one end section and one extending along the other end section, means on each end section engaging the convolutions of the spiral element that extends along it whereby the end sections may be moved toward and from each other on rotation of the spiral elements, and a housing receiving said end sections and enclosing the said spiral elements.

9. A headgear having a head band with opposed end portions, one of said end portions having a projection thereon, a spirally wound coil element having convolutions in which said projection is engaged, means for rotating the coil element to impart rectilinear movement to the projection whereby to adjust one end of the head band relatively to the other, and means for retaining the coil element on the head band and in engagement with the projection.

10. A headgear having a head band with opposed end portions, a curved housing in which the end portions are received, a pair of oppositely turned resilient coils in the housing, one of the coils extending lengthwise over each of the opposed end portions, a common operating mechanism for turning both coils, said operating mechanism being operable at the exterior of the housing, and a projection on each end portion engaging in the convolutions of the coil which extends along it whereby to impart rectilinear movement to the respective end portions upon rotation of the coils.

11. A headgear having a head band with op-

posed end portions, a curved housing in which the end portions are received, a pair of oppositely turned resilient coils in the housing, one of the coils extending lengthwise over each of the opposed end portions, a common operating mechanism for turning both coils, said operating mechanism being operable at the exterior of the housing, and a projection on each end portion engaging in the convolutions of the coil which extends along it whereby to impart rectilinear movement to the respective end portions upon rotation of the coils, the end portions of the head band, the

10

housing, and the coils all being curved to conform generally to the curvature of the head of the wearer.
